FLUID STORAGE AND PROTECTIVE SYSTEM

Charles David Beaumont, United States Navy

Application July 23, 1945, Serial No. 606,692

8 Claims. (Cl. 222—1)

(Granted under the act of March 3, 1883, as
amended April 30, 1928; 370 O. G. 757)

1

This invention relates to a fluid storage system and more particularly to a method and means for storing and protecting fluid fuel in a novel system of fuel storage chambers for use on board ship.

The storage of high octane gasoline on board ship for its complement of aircraft, particularly carriers, is dangerous especially when part of the gasoline is exhausted for the reason that the mixture of gasoline vapor and air which occupies the partially empty storage space is highly explosive and penetration by an enemy bomb or torpedo or exposure to undue heat from fire adjacent to the storage space will result in explosions and fire. To overcome the occurrence of these vapor filled spaces it has been the practice to displace the gasoline as it is exhausted with an inert fluid such as a gas or water. Salt water has been found to be the most practical displacing fluid for use on ships because of the ease of obtaining it and of disposing of it. In prior storage systems one of the objectionable features has been that if a leak or break occurs in one part of the system substantially all of the gasoline is lost. Another objectionable feature has been inability to utilize the maximum amount of gasoline in the system.

It is an object of this invention to provide an improved gasoline storage system in which the use of salt water to displace the exhausted gasoline will be availed of to afford a maximum safety from fire hazard from within the ship or from bomb damage from without the ship; which will conserve a maximum of fuel in case of rupture in a part of the system and from which a maximum quantity of fuel may be drawn off without contamination with salt water.

A further object of the invention is the provision of a storage system for any fluid which it is desired to protect from fire, explosion, harmful rays such as ultra-violet and radioactive rays, and the like.

As illustrated herein the fuel storage system comprises a plurality of chambers arranged in series with an outlet near the top of one of the chambers through which the fuel is withdrawn and conducted to its point of use, an inlet near the bottom of another one of the chambers through which salt water is admitted to displace the fuel being withdrawn and means connecting the top of each of the chambers in the series with the bottom of its adjacent chamber whereby the fuel drawn from the one chamber is replaced by that flowing into it from the adjacent chamber.

2

As the fuel is withdrawn from the successive chambers beginning with the last chamber salt water flows by gravity into the space formerly occupied by the gasoline. More specifically the chambers are nested so that the inner chambers are protected by the envelopes formed by the surrounding outer chambers, each chamber being connected by a conduit to the chamber adjacent thereto so that the fluid fuel flows from the top of the outermost chamber inwardly toward the innermost chamber and is withdrawn through an outlet near the top of the innermost chamber. In any succeeding chamber the flow of fuel is from the top of one chamber to the bottom of the next. Hence a rupture of one chamber will not drain the gasoline from the remaining chambers in the system. The innermost chamber from which the fuel is withdrawn for use is relatively small in comparison to the total volume of the system and the outlet conduit is located so that its suction end is about midway between the top and bottom of this chamber, hence a maximum amount of fuel may be withdrawn from the system without contamination with salt water.

Broadly stated, the invention contemplates a storage system comprised of a nested series of interconnected tanks in which the stored fluid is replaced by and gradually surrounded by a protective fluid, not readily miscible with the stored fluid, as the stored fluid is sequentially withdrawn from the ends of the tanks to which it will naturally gravitate when the protective fluid is fed to the other ends of the tanks.

The invention will now be described in more detail with reference to the accompanying drawings in which:

Fig. 1 is a side elevation of my improved storage system fore and aft;

Fig. 2 is a section on the line 2—2 of Fig. 1;

Fig. 3 is a fragmentary section on the line 3—3 of Fig. 2;

Fig. 4 is a cross section of a somewhat modified arrangement as employed in an aircraft carrier taken on the line 4—4 of Fig. 5; and

Fig. 5 is a plan view taken on the line 5—5 of Fig. 4.

Referring to Figs. 1—3 there is shown schematically an arrangement of chambers which constitute the present gasoline storage system. The chambers are arranged to form a substantially rectangular bulkhead 10 which consist essentially of a horizontally disposed chamber 12 arranged to overlie a plurality of nested chambers 14 Fig. 2. The chambers 14 are disposed in a

vertical position and their upper ends are protected by the overlying chamber 12. As illustrated in Fig. 1 the chamber 12 has a horizontal portion 16 which is coextensive in area of the underlying nested chambers 14, Fig. 2, and a vertical depending portion 16' which extends downwardly at one end of the nested tanks (the right hand end as viewed in Fig. 1) to the bottom thereof. This depending portion or leg 16' which is comparatively narrow is located substantially at the center of the right end of the nested chambers as seen in Fig. 2 and a space is left between the vertical chambers to accommodate the leg 16' so that its outer surface is flush with the surface of the other end chambers. The leg 16' is provided with an inlet conduit 18 (Fig. 1) which extends from the top thereof to a point near the bottom. A diffuser 20 is attached to the lower end of the conduit 18 so that liquid preferably sea water which flows downwardly through the conduit 18 will not cause turbulence as it flows out at the lower end of the conduit and hence will not mix the sea water with the gasoline which floats on the surface of the water as the water flows into the bottom of the chamber. The left hand end of the chamber 16, as seen in Fig. 1, overlies one of the vertical chambers in the nested arrangement of chambers namely, chamber 22 which lies along the left end of the storage system. The chamber 16 is connected to the chamber 22 by a conduit 24 which extends from a point near the top of chamber 16 into the chamber 22 and terminates near the bottom thereof in a diffuser 28. The chamber 22 is in turn connected to a chamber 30 underlying the chamber 16 which lies along the rear side of the storage system, as shown in Fig. 2, and the chambers 22 and 30 are connected, as illustrated in Fig. 3, by a conduit 32. The conduit 32 extends from an opening 34 near the top of the chamber 22 to a point near the bottom of the chamber 30 and terminates in a diffuser 36. It will be seen by reference to Fig. 2 that the entire system consists of a series of chambers similar to those described above, connected in a similar fashion and hence they will not be described individually.

Briefly the chamber 30 is connected to chamber 38, and chamber 38 is connected to a chamber 40 in the same fashion that chambers 22 and 30 are connected. At the right end of the system in order that the leg 16' will not project a space is left between chambers 40 and 42 to accommodate the leg. These two chambers 40 and 42 are interconnected by a by-pass conduit 44 in lieu of the usual connections. The chamber 42, however, is connected to a chamber 46 as heretofore described and likewise the remaining chambers in the series which include chambers 48, 50, 52, 54, 56, 58, 60, 62, 64, 66, 68, 70 and 72. The chamber 72, which forms the last chamber in the series, as will be seen, is relatively small in volume in comparison with the total volume of the storage system and the cross section of this chamber is also comparatively small hence when the fluid fuel is withdrawn from this chamber through an exit pipe 74 there is a minimum of surface contact between the gasoline and water and hence the possibility of gasoline contaminated with water is minimized. The exit pipe 74 extends into the chamber 72 to a point which is approximately midway between the top and bottom of the chamber and hence the fuel may be drawn off through this pipe until water occupies the lower half of the chamber. Due to the comparatively small volume of the chamber it

is clear that a maximum amount of fuel may be exhausted from the system without danger of contamination with sea water.

In this system it is a practice to displace the fuel which is withdrawn through the conduit 74 by sea water admitted through the inlet 18 and hence the chambers are progressively filled with sea water as the fuel is withdrawn therefrom in the order mentioned. This affords protection for the system for as more and more of the fuel is exhausted a thicker and thicker envelope of heat resistant material that is water is formed around the remaining fuel.

The dotted lines *m* indicate the presence of manhole openings to permit ready access to the various chambers for inspection and cleaning. The details of these will not be described herein since they do not form an essential part of the invention.

The diagrammatic illustration of the system as described above illustrates the principle of the invention broadly. However, adaptation of this system as applied to a ship, specifically an aircraft carrier, is shown in Figs. 4 and 5 in a somewhat modified form. As shown in Fig. 4 the modified storage system includes a compartment 76 located transversely of the ship consisting of vertical side and end walls 78 and horizontal bottom and top walls 80 and 82 welded together to form a liquid tight bunker. Within this outer compartment there is disposed in spaced relation longitudinally of the ship a pair of vertical walls 84 which are connected at their upper edges to horizontal wall 82, at their lower edges to the bottom wall 80, and at their vertical edges to the end walls 78. The spaces 85 formed by this construction may be filled with salt water or with an inert gas and thereby provide a fire resistant wall along the longitudinal sides of the compartment. A wall 86 is also provided which divides the space between walls 84 into equal portions, this wall being welded at its top and bottom edges to the walls 82 and 80, and at its vertical edges to the end walls 78. Inwardly of the walls 84 and 86 are two chambers 90 formed by side, end and top walls 88. The lower edges of these walls 88 are welded to the bottom wall 80, the vertical edges to the opposite sides of the wall 86 and the top edges to the wall 86. The chambers 90 afforded by this construction, that is between the walls 80, 82, 84 and 88, are filled with an inert gas thereby providing a complete heat insulating envelope which provides protection for the gasoline containing chambers now to be described. Inwardly of the walls 88 and spaced therefrom, that is within the chambers 90 are another pair of chambers 95 formed by side, end and top walls 96. These walls are welded at their bottom edges to the wall 80 and at their side and top edges to the wall 86. The spaces 95 which are formed by the walls, 80, 86, 88 and 96 afford the outermost storage chamber for a fluid fuel such as high octane gasoline hence it will be observed that the gasoline in this chamber is protected by an insulating layer of inert gas and a layer of salt water. A conduit 94 is arranged to extend downwardly from above the wall 82 through the wall 82, the wall 88 and downwardly through the chamber 95 to a point near the bottom where it terminates in a diffuser 97. This conduit 94 is connected to some source of water supply such as a tank filled with salt water from which the water may flow by gravity, or to a pump by which water will be forced, into the chamber 95.

A pair of chambers 98 are formed at opposite sides of the wall 86 by the walls 96 which provide storage space for additional gasoline. Within the chambers 98 there are disposed cylindrical chambers 106, the lower ends of which rest on and are welded to a horizontal structural member 108 spaced within chamber 98 from the bottom wall 88 and the upper ends of which are welded to portions of the horizontal of the wall 86. Conduits 100 extend from the chambers 95 through the horizontal portions of the walls 96 downwardly through the chambers 98 to a point near the bottom where they terminate in diffusers 102. An inlet 110 is formed in each cylindrical chamber 106 to which there is connected a conduit 112 which extends from the inlet to a point near the bottom of the chamber where it terminates in a diffuser 114. From each of the chambers 106 there extends a conduit 116 the inlet portion of which is located about midway between the top and bottom, and the upper portion of which extends through the horizontal portion of the wall 96, the wall 88 and the wall 82 to a point where the fluid is to be delivered. It is to be observed that in Figs. 4 and 5 the construction is such that there are duplicate chambers on opposite sides of wall 86.

From the preceding description it is evident that when high octane fuel is drawn from the tank 106 through the conduit 116 the flow of fuel will be from the chamber 95 through the conduit 100 to the bottom of the chamber 98 and from the top of the chamber 98 through the conduit 112 to the bottom of the chamber 106, and finally from a point substantially midway between the bottom and top of tank 106 through the conduit 116 to the point of delivery. As the fuel is withdrawn salt water flows inwardly through the conduit 94 to the bottom of the chamber 95 and progressively displaces the fuel as it is withdrawn from the chambers 95, 98 and 106 in that order.

It is evident that this construction affords a maximum of protection since as the high octane fuel is withdrawn the space that was occupied thereby is filled with salt water so that the danger which accompanies a space filled with gas vapors is eliminated. Furthermore the presence of the layers of water and inert gas outside of the gasoline will slow up penetration of the system and will provide a protective insulation against fire or other heat which might ignite the gasoline. It is also evident from the flow that if, for example, the chamber 95 should be punctured the gasoline in chambers 98 and 106 would not drain off since the gasoline can be removed from these tanks only from the top thereof.

The invention described herein may be manufactured and used by or for the Government of the United States of America for governmental purposes without the payment of any royalties thereon or therefor.

What is claimed is:

1. An arrangement of interconnected compartments for use in a liquid fuel storage system in which the liquid fuel is displaced by water as the liquid fuel is withdrawn from the system, said system consisting of a plurality of nested compartments including at least one innermost compartment enveloped by the remainder of the plurality of compartments, an inlet for introducing water to the outermost compartment of the enveloping compartments, an outlet through which fuel may be withdrawn from the innermost compartment, and conduits connecting in series the

nested compartments so that the flow from one compartment to the next is from the top of one compartment to the bottom of the next, said series commencing with the outermost compartment, sequentially including all of the enveloping compartments, and ending with said innermost compartment.

2. An arrangement of protective and interconnected chambers for use in a closed liquid fuel storage system in which the liquid fuel is displaced by water as the liquid fuel is withdrawn from the system, said arrangement consisting of a plurality of nested chambers, including at least one innermost chamber enveloped by the remainder of said plurality of chambers the outer chamber of the enveloping chamber being isolated from the remaining chambers and filled with an inert gas, an inlet conduit associated with the next chamber of the enveloping chambers through which water may be introduced to the bottom of said chamber, an outlet associated with the innermost chamber through which fuel may be withdrawn from the near top thereof, and means connecting in series each of the nested chambers with its adjacent chamber comprising a conduit arranged so that its inlet end is at the top of one chamber and its outlet end is at the bottom of the adjacent succeeding chamber, said series commencing with the chamber to which water is first introduced, sequentially including all of the enveloping chambers, and ending with said innermost chamber.

3. An arrangement of interconnected chambers for use in a closed liquid fuel storage system in which the liquid fuel is displaced by water as the liquid fuel is withdrawn from the system, said arrangement consisting of a plurality of vertically disposed nested chambers including at least one innermost chamber surrounded by the remainder of said plurality of chambers, and a chamber overlying the upper ends of said nested chambers, means arranged to deliver water to the bottom of the overlying chamber, means connecting the top of the overlying chamber, and the top of each of the surrounding chambers from the outermost inwardly with the bottom of its adjacent succeeding chamber, and means near the top of the innermost chamber through which fluid may be withdrawn.

4. An arrangement of interconnected chambers for use in a closed liquid fuel storage system in which the liquid fuel is displaced by water as the liquid fuel is withdrawn from the system, said arrangement consisting of a plurality of vertically disposed nested chambers including at least one innermost chamber surrounded by the remainder of said plurality of chambers, a chamber disposed over the upper ends of the vertical chambers, said chamber having a depending leg terminating at the bottom of the vertical chambers, means for introducing water to the bottom of the depending leg of said overlying chamber, means connecting the top of the overlying chamber the top of each of the succeeding surrounding chambers with the bottom of an adjacent succeeding chamber, and a discharge outlet near the top of the innermost chamber through which liquid may be withdrawn.

5. An arrangement of interconnected chambers for use in a closed liquid fuel storage system in which the liquid fuel is displaced by water as the liquid fuel is withdrawn from the system, said arrangement consisting of a plurality of nested chambers including at least one innermost chamber enveloped by the remainder of said plurality of chambers, an inlet conduit in the outermost

chamber of the enveloping chambers for introducing water to the bottom thereof, said inlet conduit having a diffuser at the lower end thereof, conduits connecting the top of the outermost chamber and each of the succeeding chambers with the bottom of an adjacent succeeding chamber, each of said conduits having a diffuser at lower end, and a conduit near the top of the innermost chamber through which liquid may be withdrawn.

6. An arrangement of interconnected chambers for use in a closed liquid fuel storage system in which the liquid fuel is displaced by water as the liquid fuel is withdrawn from the system, said arrangement comprising an inner chamber from which the fuel is withdrawn said chamber being of comparatively small cross-sectional area, an intermediate chamber completely enclosing the first named chamber and of much larger cross-section area and an outside chamber enclosing said intermediate chamber, means connecting the top of the outside chamber with the bottom of the intermediate chamber and the top of the intermediate chamber with the bottom of the inner chamber and a conduit for introducing water into the bottom of the outside chamber.

7. A system for storing a fluid and protecting it with a fluid of different specific gravity not readily miscible therewith comprising a plurality of tanks, at least one of said tanks being enveloped at the top and sides by the remainder of the plurality of tanks, a conduit for withdrawing stored fluid from a point intermediate the top and bottom of said enveloped tank, a conduit for supplying protective fluid to one of said remainder of the plurality of tanks and connected to the end thereof to which the protective fluid naturally gravitates when the plurality of tanks are substantially full of stored fluid, conduits for connecting in series said plurality of tanks by connecting the end of one tank to which the stored fluid naturally gravitates to the end of another tank to which the protective fluid naturally

gravitates, said series commencing with the tank to which said protective fluid is first supplied, sequentially including all of said remainder of the plurality of tanks, and ending with said enveloped tank.

5 8. The method of storing and protecting a fluid fuel not readily miscible with water, wherein said fuel upon withdrawal is displaced by water and wherein said fuel has a specific gravity different from that of water; said method including the 10 following steps: storing said fuel in a plurality of containers; enveloping at least one of said containers at the top and sides by the remainder of said containers; connecting said plurality in series by conduit means connecting that portion of one of said containers to which said fluid naturally gravitates, to that portion of another of said containers to which said water naturally gravitates, whereby said series starts with that one of said containers to which said water is initially supplied, sequentially includes all of said remainder and terminates with said enveloped container; supplying said water to said series at that portion of said starting container to which said water naturally gravitates when said plurality of containers is substantially filled with said fuel; and withdrawing said stored fluid from a point intermediate the top and bottom of said enveloped container.
